CANE FOR AN INVALID

John W. Maxwell, Mentor, Ohio

Application July 7, 1958, Serial No. 51,677

Term of patent 14 years

(Cl. D88—4)

FIG. 1

FIG. 2

FIG. 3

FIG. 4

Figure 1 is a perspective view of a cane for an invalid showing my design, the top portion of the cane thereof being foreshortened for convenience of illustration;

Figure 2 is a side elevational view on a reduced scale showing the cane in its extended position;

Figure 3 is a side elevational view thereof; and

Figure 4 is a rear elevational view showing the cane in its collapsed position.

The dominant feature of my design resides in those portions shown in full lines on the drawing.

I claim:

The ornamental design for a cane for an invalid, as shown and described.
